SELF-PRIMING PUMP

Richard G. Barzen, Kansas City, Mo.

Application September 7, 1933, Serial No. 688,481

1 Claim. (Cl. 103—113)

The present invention relates to pump construction, and one primary object in view is to provide a novel and improved as well as more efficient construction characterized by a self-priming function, and in which provision is made for the self-priming action with a minimum of complication as regards structural details.

Accordingly, the improved construction comprises a centrifugal pump unit provided with means for automatically maintaining a priming action by the centrifugal force of the pump operating to produce a circular wash of priming fluid around the housing forming the impeller chamber, after which the priming feature, while no longer operative, in no way obstructs or diminishes the primary pumping operation of the unit. The priming function depends upon a limited supply of priming fluid maintained within the pump-casing surrounding the housing of the impeller chamber and communicating with the latter through a port so located as to subject the priming fluid most effectively to the influence of the central or suctional region of the impeller chamber, while the wash of the fluid around the exterior of the impeller housing, due to the impeller's operation, is maintained free and unobstructed for producing the most effective priming action during the preliminary operation of the pump for that purpose. The fundamental characteristic of the improved construction is the provision of such means as will automatically maintain an efficient flow of priming liquid for the needs of the impeller in the priming action and thereafter cause such flow of priming liquid to be dispensed with as a natural consequence of the centrifugal action involved in the normal operation of the pump.

It is further sought to provide a construction in which an improved supported relation is afforded the pump structure proper, eliminating bearing features from the pump unit itself and relieving it of stresses that would otherwise be imposed upon the pump casing, and at the same time preserving a proper effective seal between the shaft bearings and the water spaces.

A further feature of improvement is to be found in an improved packing structure for housing the adjoining end of the impeller shaft and providing a most effective lubricant seal therefor.

With the foregoing general objects in view, the invention will now be described by reference to the accompanying drawing illustrating the preferred form of embodiment of the proposed improvements, after which those features and com-

bination deemed to be novel will particularly be set forth and claimed.

In the drawing—

Figure 1 is a vertical sectional elevation, representing a section taken on the line 1—1 of Figure 2 and illustrating a pump apparatus constructed in accordance with the present invention;

Figure 2 is a vertical sectional view, representing a section taken on the line 2—2 of Figure 1;

Figure 3 is an enlarged sectional detail view showing the end of the impeller shaft and improved packing construction for same; and

Figures 4 and 5 are transverse sections taken on the lines 4—4 and 5—5, respectively, of Figure 3.

Referring now to the drawing in detail, this illustrates my improved construction as comprising a supporting standard 10 provided with suitable bearings 12 for the journalling of a shaft 14 to which power may be transmitted in any preferred manner, as by means of a pulley 15. The standard 10 is formed with a supporting flange 16 to which is secured, as by means of screws 17, the outer edge of a casting 18 which is formed with a central packing housing 20 for the corresponding portion of the shaft 14, and also with a flange 21 for the attachment, as by the screws 22, of the pump casing 24, all as illustrated in Figure 1. The casing 24 is constructed to provide an outer chamber 25 and also an interior volute shell or housing 26 forming an impeller chamber 27 having its discharge outlet 28 at the bottom of the chamber 25 and facing in the direction of the water circulation as produced by the action of the impeller member 29, around the chamber 25 to the discharge outlet 30 therefrom. The impeller member 29 is of conventional form having the vanes or blades 32, and secured by a conical bushing 33, key 31 and nut 34 to the end of the shaft 14; its hub portion 29' also has a machined fit within the hub recess 18' of the casting 18, as well as machined surfaces 35 at the areas of contact between the outer portions of the impeller and the corresponding faces of said casting, as clearly indicated in Figure 1.

The shell 26 connects with the outer side of the casing 24 by means of the central neck portion or annular partition 36 forming a central or axial intake passage 37 to the impeller chamber 27, the entrance to which passage 37 is by way of an intake casting or housing 38 attached by screws 40 to the outer face of the casing 24.

In the lower side of the neck or partition 36

is provided a passage or port 42 arranged at an angle (of approximately 65° to 70°) to the axis of the impeller, or in such angular position as to direct water from the chamber 25 (in the priming operation) into the interior of the impeller at the points best adapted for effectiveness in the circulation of the water by means of the impeller vanes or blades.

An inspection and clean-out opening 43 (adapted to be covered by a suitable cover plate—not shown) is provided in the outer face of the casing 24, below the intake housing 38.

In the priming operation of the pump, it will be understood that the chamber 25 is maintained partly full of water and the rotation of the impeller (in the direction indicated by the arrow in Figure 2) produces a circular wash of this water through said chamber, which tends to seal the pump discharge and creates a suctional action within the intake line to the pump. It will also be noted that the port or passage 42 is located just above the discharge outlet from the impeller chamber 27, which is just that position best adapted to trap the water discharged from said port into the impeller chamber between the series of impeller vanes or blades 32 as they successively pass said discharge outlet 28; and the angle of this port or passage 42 is also that which is best adapted to transmit the influence of the suctional action produced within the central zone of the impeller chamber. That is to say, the position and angle of the port or passage 42 are both such as to best serve the double function of supplying the water from the chamber 25 in proper fashion to the impeller blades, and of promoting the movement of the water for this purpose by as direct transmission as possible of the suctional action from the axial region of the impeller through said port 42 to the chamber 25.

The air drawn in through the intake 37 is trapped by the circulating water and escapes through the outlet 30 from the pump, and since during the priming action all the water supplied to the impeller reaches it through the port 42, and in an amount which is of course considerably less than the pump's capacity, the actual priming action will take place in a more or less intermittent or pulsating manner, for the restricted feed of water to the impeller through said port will result in the impeller becoming momentarily air-bound to a certain degree until sufficient water is again sucked through said port into the impeller chamber to maintain the full priming effect of the impeller, thereby trapping more air from the intake line and discharging it from the pump. This pulsating effect is evidenced by slight fluctuations in the degree of vacuum produced in the intake, which gradually increases until the required degree is secured for obtaining the required suctional lift on the intake side of the pump. When this point is reached the action of the impeller will maintain the movement of the water around the outer limits of the casing and with such centrifugal effect as to overcome any tendency of the water to move inward through the port 42 into the impeller chamber. In this connection it will be observed that by virtue of the fact that a free and unobstructed passage is provided for the circulation of water in the outer casing around the impeller housing and its neck portion 36, no hindrance is offered to the centrifugal movement of the water, and this open character of all the pumping passages and the elimination of any recirculation following the preliminary

priming operation has the effect of maintaining the full pumping capacity of the unit during the normal operation thereof.

The free and unobstructed character of the flow space around the impeller housing and its intake connection also promotes such vigorous centrifugal movement of the water as to wash and scour the flow passage clean and free of any deposit of foreign matter,—eliminating the necessity of providing screens or the like in most pumping operations.

If desired, a suitable flap valve 39, hinged to a plate 41, may be secured in place at the entrance to the intake housing 38, for the purpose of automatically cutting off communication from the induction pipe when the operation of the pump is stopped, and thus keeping a sufficient supply of water in the pump casing for use in the next priming operation.

Within the recess provided by the hub portion 20 of the casting 18 around the end portion of the shaft 14 I provide an improved packing structure which comprises a plurality of grooved or channeled leather gaskets 44, in two sets, one for each end of said recess; and between these two sets of gaskets I interpose a single compression spring 45 seating against rings 46 having grooves 46' for engaging the ridges formed by the grooves or channels of said gaskets. The spring 45 is of sufficient strength to firmly compress the gaskets against the end cap plates 47 held in place by the screws 48. Thus it will be seen that the action of the spring tends to crowd the gaskets apart in such a way as to spread their edges against the shaft 14 and the interior of the hub 20, respectively; and while this serves to maintain a constant and uniform seal around the end of the shaft, it is apparent that with the gaskets flaring outwardly in opposite directions towards the ends of the packing structure, this permits grease to work out past the edges of the gaskets, but opposes any pressure of air or water seeking to enter the opposite ends of the packing, i. e., at the ends of the recess within said housing portion 20. A grease cup 49 and duct 50 are provided for feeding suitable lubricant to the space occupied by the spring 45.

That object of the invention is also accomplished which aims to relieve the pump casing itself of any bearing strain, since the construction provides for attachment of the casing to a bearing structure which is otherwise supported, that is, by the attachment of one side of said casing to the flange 21 of the casting 18. Thus, in addition to providing not only a more simple as well as more sightly construction, the pump unit is relieved of much of the tendency to distortion to which it is usually subjected in the usual conventional designs.

It will therefore be seen that I have provided a practical and highly efficient arrangement and construction for carrying out all the desired objects of the invention as hereinbefore stated; and while I have illustrated and described what I now regard as the preferred form of embodiment thereof I desire to reserve the right to make whatever changes or modifications may fairly fall within the spirit and scope of the appended claims.

Having described the invention, what I claim is:

A self-priming pump construction comprising, a pump casing of approximately cylindrical form having a discharge outlet at its top portion, one

of the side walls of the casing having a hollow inwardly projecting neck portion providing an intake passage, a volute impeller housing connected integrally both with the opposite side wall and also with the inner end of said neck portion and having an outlet at the lowermost portion of said housing in approximately tangential relation to the interior wall of the casing for discharging into the outer space within the casing surrounding said housing, said outer space within the casing surrounding both said housing and said neck portion being undivided as well as entirely open and unobstructed to form a single flow-space permitting free circulation of the

priming liquid in one stream following a substantially circular path around both said housing and said neck portion, and a rotary impeller member operating within said housing about an axis aligned centrally with said intake passage, the bottom of said neck portion having a port in the same vertical plane with the axis of said impeller member and positioned to direct a jet of priming liquid toward the central portion of the impeller housing, said housing outlet being also located 10 in said vertical plane and below the level of said port. 5

RICHARD G. BARZEN.
